UNITED STATES PATENT OFFICE.

WILLIAM M. DAVIDSON, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

REINFORCED ROTARY PIVOTED HAMMER.

Application filed August 21, 1922. Serial No. 583,238.

To all whom it may concern:

Be it known that I, WILLIAM M. DAVIDSON, a citizen of the United States, residing at St. Louis, State of Missouri, have invented certain new and useful Improvements in Reinforced Rotary Pivoted Hammers, of which the following is a specification.

This invention relates to certain new and useful improvements in reinforced rotary pivoted hammers, the peculiarities of which will be hereinafter fully described and claimed.

The main object of my invention is the provision of an effective reinforcement for the cast head of a rotary pivoted hammer having a shank of ductile metal such as wrought iron or steel; and secondly, the arrangement of such reinforcement in the cast head with respect to the shank, that the reinforcement is connected to the shank by detachable rivets or bolts.

In the accompanying drawing on which like reference numerals indicate corresponding parts, Fig. 1 represents a side elevation of a hammer embodying my improvements; and Fig. 2, a partial section on the line 2—2 on Fig. 1, and an edge view of the shank.

The numeral 4 designates a flat bar shank of wrought iron or steel having a hole 5 at one end for pivotal mounting in a rotor as usual in this form of hammer. A cast head 6 is provided with downwardly extending walls 7 forming a rectangular socket adapted to receive the outer end 8 of the shank that is slidingly mounted therein as shown in the figures. The walls 7 entirely surround the end of the shank, and the head beyond the shank is preferably larger as shown in the figures, and in practice it has been found that the line of fracture of the head is commonly in or near the transverse plane 3—3,— although the fracture some times occurs at or near the end of the hammer shank in its socket.

My plan for reinforcement provides circular or oblong ring shaped pieces of

wrought iron or steel cast in the head substantially as shown. Thus a ring 9, practically circular, is located in the plane of the flat dimension of the shank as shown in Fig. 2, and with the said transverse plane 3 traversing the ring substantially on its diameter as shown in Fig. 1. It is understood that the flat dimension of the bar and the rings themselves are disposed in planes of revolution so that the edges of shank and preferably also of the rings are presented to the front. Other reinforcement extends downward from the head into the side walls 7, as shown by the elongated rings 9', such a distance that the fastening rivets 10 pass through the loop of 9' rings and through the end of the shank in the socket. Should any fracture occur therefore at or near the plane 3, the rings will hold the outer end of the head from disengagement. Should the fracture occur further inward such as below the head 6, the elongated rings 9' will hold the members together, and the rivets will tie the elongated rings to the shank itself whatever the position or location of the fracture that may ordinarily occur in the cast head.

Thus a socket hammer, so called, using metal of different characteristics may be rendered safe by my reinforcement against all ordinary fractures that may occur in the cast head.

I claim:

In a rotary pivoted hammer, the combination with a shank, a cast head liable to fracture having walls forming a slotted recess in which is slidingly mounted the end of said shank, and transverse fastening means passing through said shank and adjacent wall portions of said head, of ductile elongated ring reinforcements located in said wall portions and outer head portions, and embracing said fastening means, substantially as described and for the purpose set forth.

In testimony whereof I have affixed my signature.

WILLIAM M. DAVIDSON.
